UNITED STATES PATENT OFFICE

FRANK R. OWENS, OF BEAVER CROSSING, NEBRASKA, ASSIGNOR TO OWENS PARACHUTE CORPORATION, OF BEAVER CROSSING, NEBRASKA, A CORPORATION OF NEBRASKA

PARACHUTE

Original No. 1,887,884, dated October 16, 1928, Serial No. 212,055, filed August 10, 1927. Application for reissue filed October 15, 1930. Serial No. 488,956.

The present invention relates to parachutes and has for its principal object to provide a device of this character which will open without fail when making a descent therewith. Other objects are simplicity and 5 cheapness of construction. Further objects and advantages will appear from the following specification and claims.

In the drawings:
10 Figure 1 is a sectional view showing the parachute when open.

Figure 2 is a bottom plan view of the parachute when open.

Figure 3 is a detail view showing the stop 15 which prevents the parachute from opening beyond the desired spread.

Describing the invention in detail, provided within the dome of the parachute is a canvas tube 13 secured at its upper end 20 to the body 10 and in spaced relation thereto by means of straps 14 of canvas or other suitable material which may be sewed to the body portion 10 and to the sides of the cylinder. There may be any number of these 25 straps, but I prefer to use four, spaced at equal intervals about the cylinder. Bound in the lower end of the tube 13 I provide a metallic ring 15 which is held to the tube by folding the material thereabout and forming 30 a line of stitches 16 therein.

A rope 17 to which the operator may hold in making a descent has its upper end attached to the tube 13 by means of branches 35 18 spliced thereto and having their upper ends looped at 19 through apertures 20 about the ring 15. The lower edge of the dome of the parachute is folded upon itself to form a hem 21 and is provided with spaced apertures 22, the edges of which are bound 40 by eyelets 23 and secured in these eyelets I provide a plurality of tie ropes 24, the upper ends of which are secured in the eyelets 23 and the lower ends converge to connect with the flange 25 formed on the ferrule 26 which 45 is slidable on the rope 17. The ropes are connected to the flange 25 by looping the rope as at 27 through apertures 28 formed in said flange.

A stop 29 is provided on the rope above 50 the ferrule and is secured to the rope against

sliding therealong by any suitable means as by a set screw 30. This stop is locked in such a position along the rope 17 so as to prevent the dome of the parachute from turning wrong side out. The tube 13, it will be 55 noted, is of such a length that when the dome of the parachute is collapsed thereabout the lower end of the tube will project beyond the lower end of the dome of the parachute.

In operation it will be readily seen that when an operator is making a descent from a flying machine, when he throws the parachute to the breeze air will immediately pass through the tube 13 for the reason that the lower end thereof is held constantly open by 60 the ring 15. Air passing upward through the tube will spread out from its upper end, filling the dome of the parachute and causing it to spread to open position, as shown in Figure 1. It is to be understood that the 65 weight of the operator will all be on the lower end of the tube 13 until the dome of the parachute is fully open, from which time the weight will be on the ropes 24 and the parachute will support practically all 70 of the weight. It will be readily seen that by the above construction danger of making a jump and having the parachute fail to open is practically eliminated and danger from 75 said leaps in the air will be greatly minimized.

Having described my invention what I claim is:

1. A parachute having a dome of flexible material, a tube secured therein by one end, 85 said end being in spaced relation to the dome of the parachute, a rigid ring secured in the lower end of the tube, a rope secured to said ring, ropes secured to the lower edge of the dome of the parachute and having a slideable 90 connection with the first mentioned rope.

2. A parachute comprising a dome of flexible material, a tubular member having one end thereof secured within the dome of the 95 parachute and in spaced relation to the walls thereof, a rigid ring secured in the lower end of the tube, a rope secured to said ring, a plurality of ropes connected in spaced relation to the lower edge of the dome of the 100 parachute and having a sliding connection with

the rope secured to the tube, said tube being of a length to project below the lower end of the body of the parachute when the same is collapsed about said tube.

3. In a parachute, a body portion of flexible material when opened in the form of a dome, a flexible tubular member having flexible connection with the top of the dome and being of a length to project beyond the lower end of the dome when the dome is collapsed thereabout, a ring secured in the lower end of the tube, a rope having branches, connected to the tube, ropes connected to the lower edge of the dome of the parachute and having sliding connection with the rope connected to the tube, and a stop for preventing the sliding connection from sliding beyond a predetermined point on said rope.

4. In a parachute, a canopy, shroud lines connected with the edges of said canopy, a cable connected with a center portion of said canopy and adapted to become taut while said shroud lines are yet loose as the parachute goes into operation, a stop member secured to said shroud lines, and a second stop member secured to said cable and adapted to engage the first said stop member only after a predetermined relative movement of said cable with respect to said shroud lines.

5. In a parachute, a canopy, shroud lines connected with edge portions of said canopy, a cable connected with a center portion of said canopy and adapted to receive the parachute load wholly and automatically upon initial opening, means connecting the lower ends of said shroud lines together, and means comprising a lost-motion connection between said shroud line connecting means and cable operative upon opening of said canopy to a predetermined extent to transfer a portion of the tension of a load from said cable onto said shroud lines.

6. In a parachute, a canopy, shroud lines connected with edge portions of said canopy, means connected with a center portion of said canopy and depending therefrom between said shroud lines, means connecting said shroud lines in relatively fixed relation at a predetermined distance from said canopy, means adapted for securing a load to the first said means, and means initially unconnected with said connecting means for automatically transferring at least a portion of the load from the first said means to said shroud lines after a predetermined opening of said canopy.

7. In a parachute, a canopy, a plurality of shroud lines secured and depending from spaced places adjacent the edge of said canopy, a flexible member secured to a center portion of said canopy and depending therefrom between said shroud lines, a stop member secured to said shroud lines, a second stop member secured to said flexible member, said stop members being interengageable only

after a predetermined relative movement to limit upward movement of said shroud lines relative to said flexible member beyond a predetermined distance and means depending from said second stop member for engagement with a load.

8. In a parachute, a canopy, a plurality of shroud lines secured to and depending from spaced places adjacent the edge of said canopy, a flexible member secured to a center portion of said canopy and depending therefrom between said shroud lines, a stop member secured to said shroud lines and holding said shroud lines in relatively fixed spaced relation to one another, a second stop member secured to said flexible member, said stop members being interengageable after a predetermined relative movement to limit upward movement of said shroud lines relative to said flexible member beyond a predetermined distance, and means depending from said stop members when interengaged for engagement with a load.

9. A parachute comprising a canopy, shroud lines connected at one end of each with an edge portion of said canopy, flexible means connected with a center portion of the normal underside of said canopy and depending between said shroud lines, means secured to said shroud lines for guiding said flexible means with respect to and between said shroud lines, and an abutment secured to said flexible means between said guide means and the connection of said flexible means to a center portion of the canopy and normally engageable with said guide means only after a predetermined opening of said canopy.

In witness whereof I have affixed my signature.

FRANK R. OWENS.
